United States Patent Office

Des. 192,887
Patented May 22, 1962

192,887

BOTTLE

Donald P. Denhoff and Dale R. Brown, Saline, Mich.,
assignors to Hoover Ball and Bearing Company, Ann Arbor, Mich., a corporation of Michigan

Filed July 27, 1961, Ser. No. 66,098

Term of patent 14 years

(Cl. D58—8)

The side not shown is the same as the side shown.

We claim:

The ornamental design for a bottle, as shown and described.
